UNITED STATES PATENT OFFICE.

JOSEPH J. PHILLIPPS, OF BROOKLYN, NEW YORK.

DESIGN FOR A MEMORIAL-TABLET.

SPECIFICATION forming part of Design No. 16,565, dated March 9, 1886.

Application filed December 18, 1885. Serial No. 186,096. Term of patent 7 years.

To all whom it may concern:

Be it known that I, JOSEPH J. PHILLIPPS, a citizen of the United States, residing at Brooklyn, in the county of Kings and State of New York, have invented and produced a new and original Design for Memorial Tablets, of which the following is a specification, reference being had therein to the accompanying drawings.

The leading feature of my design consists in the representation of a cross having a wreath in the center, a series of rays diverging from each inner angle of the cross, and above the cross is an ornamentation, as shown; but this may sometimes be omitted without altering the leading feature of the design. Surrounding the whole is a border, which consists of a running vine inclosed between lines with the cen-

ter of the sides of the border and the corners of scroll-work, and with the top and bottom lines of the border curved in the centers, as shown.

What I claim as new is—

The memorial-tablet herein shown and described, consisting of the representation of a cross with a wreath in the center, rays at the inner angles of the cross, and a border inclosing the whole.

In testimony whereof I affix my signature, in presence of two witnesses, this 12th day of December, 1885.

JOSEPH J. PHILLIPPS.
